UNITED STATES PATENT OFFICE

151,320

DESIGN FOR A COMBINED RADIO AND
BED LAMP

Lewis R. Brothers, North Hollywood, Calif.

Application July 21, 1947, Serial No. 140,426

Term of patent 14 years

(Cl. D56—4)

To all whom it may concern:

Be it known that I, Lewis R. Brothers, a citizen of the United States, residing at North Hollywood, in the county of Los Angeles, State of California, have invented a new, original, and ornamental Design for Combined Radio and Bed Lamp, of which the following is a specification, reference being had to the accompanying drawing, forming part thereof.

Figure 1 is a view in front elevation of a combined radio and bed lamp, embodying my new design.

Fig. 2 is a top plan view of the same, the brackets being broken away for convenience of illustration;

Fig. 3 is a bottom plan view of the same, the brackets being broken away for convenience of illustration;

Fig. 4 is a rear view in elevation of the same;

Fig. 5 is a view in end elevation of the same; and

Fig. 6 is a perspective view of the same.

I claim:

The ornamental design for a combined radio and bed lamp, as shown.

LEWIS R. BROTHERS.
